UNITED STATES PATENT OFFICE.

LULU LOUISE JUST, OF LA SALLE, ILLINOIS.

DRESS-SHIELD.

1,078,443.

Specification of Letters Patent. Patented Nov. 11, 1913.

Application filed September 25, 1912. Serial No. 722,250.

To all whom it may concern:

Be it known that I, LULU LOUISE JUST, a citizen of the United States, and a resident of La Salle, in the county of La Salle and 5 State of Illinois, have invented a new and Improved Dress-Shield, of which the following is a full, clear, and exact description.

Among the principal objects which the present invention has in view are: to provide a shield wherein an absorbent pad is provided, which may be readily and easily removed for the purpose of laundry or replacement and which, because of the nature of the application of the pad, permits the 15 use of a smaller and cooler shield, and also serves to protect the shield; and to provide a shield of the character mentioned having a simple and efficient means for retaining said pad in position, dispensing with the use 20 of auxiliary fastening devices.

Reference is to be had to the accompanying drawings forming a part of this specification, in which similar characters of reference indicate corresponding parts in all the 25 views, and in which—

Figure 1 is a pictorial view showing in service position a dress shield constructed and arranged in accordance with the present invention; Fig. 2 is a side view of the dress shield constructed in accordance with the present invention, part of the cover of said shield being cut away to show the inserted pad and means for retaining same in service position; Fig. 3 is a cross section taken on 30 the line 3—3 in Fig. 2; and Fig. 4 is a detail view, showing in perspective a pad folded for insertion in the pad-holding pocket of the shield.

As seen in the accompanying drawings, 40 the shield is provided with the usual layer of rubber-coated material 9. As in the conventional shield, the coated surface of this material is covered by a layer 10, which is usually disposed in a sleeve and adjacent 45 the material of which the dress is constructed. In the present invention, an outer piece 11 is sewed upon the layers 9 and 10. The piece 11 is shaped to the form of the conventional shield, being slightly fulled to 50 provide pocket space between the piece 11 and the coated material 9. The outer piece 11 is provided with a pocket opening 13, the

length whereof is less than the ridge of the shield. The pocket opening 13 thus provided serves to permit the introduction of 55 the pad 12.

The pad 12 is constructed from any suitable material, such as cheesecloth, absorbent cotton, or light muslin. It is folded in the shape substantially as shown in the drawings and at Figs. 2 and 4 thereof, and the free ends of the folded pad are inserted downward into the pocket space between the layer 9 and the outer piece 10. Care is taken to fold the pad 12 to a length which, as 60 shown in Fig. 2 of the drawings, insures that the ends of the pad extend beyond the ends 14 of the pocket opening 13. The material surrounding the pocket opening prevents the displacement of the pad 12. The 65 pad 12, being bent to a straight fold, is raised above the pocket opening 13, as seen best in Fig. 2 of the drawings, and is exposed to direct contact with the person of the wearer. Furthermore, by reason of the 70 arrangement, the exposed portion of the pad 12 is lifted close into the armpit in a position to be brought first in contact with the moisture exuded by this part of the body. 75

With dress shields constructed and 80 arranged in accordance with the present invention, the pads 12 are frequently removed, washed and renewed. All that is required to remove the pad is to engage the same at the exposed portion, and pull the pad from 85 out of the pocket formed by the coated material 9 and the outer piece 11. When replacing a pad, each end is inserted on opposite sides of the coated material 9 and between the same and the outer piece 11 at 90 both sides of the shield.

It will be understood that the pad 12 may be made the vehicle for any suitable deodorant or perfume.

Having thus described my invention, I 95 claim as new and desire to secure by Letters Patent:—

A dress shield, comprising a moisture-proof body piece having opposite sides united to form a curved ridge to extend 100 around the arm of the wearer; a loose outer piece to cover said body piece, said outer piece having a pocket opening to register with said curved ridge; and a pad having

a straight folded upper edge the ends where-
of extend between said body piece and said
outer piece, the folded edge of said pad
being exposed and protruding above said
5 curved ridge, said pad being longer than
the pocket opening of said outer piece, to
be retained in position thereby.

In testimony whereof I have signed my
name to this specification in the presence of
two subscribing witnesses.

LULU LOUISE JUST.
